(57) **CLAIM**

The ornamental design for a remote control, as shown and described.

DESCRIPTION

FIG. 1 is a top perspective view of a remote control showing my new design;

FIG. 2 is a front elevational view thereof;

FIG. 3 is a rear elevational view thereof;

FIG. 4 is a right side elevational view thereof, the left side elevational view being a mirror image thereof; and,

FIG. 5 is a bottom plan view thereof.

The broken line showing of buttons, a battery cover, and an infrared port is for illustrative purposes only and forms no part of the claimed design.
